RAILWAY MAIL EXCHANGE DEVICE

Filed Sept. 1, 1923

Patented May 25, 1926.

1,585,698

UNITED STATES PATENT OFFICE.

HERBERT E. SMITH, OF SPOKANE, WASHINGTON, ASSIGNOR TO SPOKANE MAIL EQUIPMENT COMPANY, OF SPOKANE, WASHINGTON.

RAILWAY-MAIL-EXCHANGE DEVICE.

Application filed September 1, 1923. Serial No. 660,618.

My present invention relates to improvements in railway mail exchange devices of the rotary crane type carried by a mail car, and the invention is specifically directed to certain improvements and particular means for projecting the crane to operative position for the exchange, reception, or delivery of mail bags or pouches, and means whereby the crane may be restored to loading position in case of emergency. When carried by the mail car the exchange device is normally carried ahead of the car door and held in inoperative position exteriorly of and parallel with the side of the car. By the utilization of my invention compactly arranged means preferably located above the doorway of the car and manually operated from the interior of the car are provided for swinging the crane from its inoperative position to catch position, and manually operated means accessible from the interior of the car are also utilized as an emergency means for returning the crane to loading position from its operative position. In carrying out my invention I employ a spring device whereby the crane is retained in either inoperative or loading positions; a retaining device for holding the crane in operative or projected position; a spring device for retracting the crane after operation to the inoperative position; and means for absorbing the shock of impact in the performance of the required functions of the crane.

In the drawings I have illustrated the exchange equipment on a railway mail car in which two similarly operating devices are employed and adapted for selective use depending upon the direction of travel of the car, and in which the parts are combined and arranged according to the best mode I have thus far devised for the practical application of the principles of my invention.

Figure 1 is a transverse sectional view through the doorway at one side of a railway mail car showing the equipment of the invention with the crane in projected or operative position for supporting a mail bag for exchange or delivery, or for receiving a mail bag.

Figure 2 is a top plan view of a portion of a car roof with complementary exchange devices one of which is in operative position and the other is carried in inoperative position.

Figure 3 is a detail perspective view of a bracket for supporting and guiding one of the manually operated pull cables.

In Figure 2 two of the devices are indicated one as A and the other as B, the former being shown in operative position while the car is traveling in the direction of the arrow, said device being located in front of the doorway of the car. The device B is shown in retracted or inoperative position. Inasmuch as both devices are of similar construction and operated in the same manner, a description of the device A will suffice for setting forth the invention.

In carrying out my invention I utilize a rotary crane comprising an upright shaft 1 journaled in bearings 2 at the exterior of the car and adjacent the doorway. The shaft is provided with an upper horizontal arm 3 having attaching devices at its free end for the suspension of a mail bag or pouch, and at the lower end of the shaft a second arm 4 is provided with means for retaining the bag in upright position.

For receiving a bag of mail from the station or trackside device the lower arm is provided with a fork 5 which as shown in Figure 2 is extended horizontally from the arm 4, but when the crane is in inoperative position this fork may be turned down to vertical position and out of the way. For this purpose the arm 4 may be turned in its socket member 4' carried by the shaft 1, and the arm fixed with the socket member by use of a pin passed through openings 5' in the socket member and arm.

At the upper end of the shaft is loosely supported a clutch sleeve 6 and below this sleeve is a clutch device 7 operated through the motion of a lever 8 to disengage and uncouple the sleeve from the shaft. A spring 9 forming part of the clutch holds the clutch in engagement to retain the crane with its arms parallel with the sides of the car either in inoperative position or in loading position across the doorway of the car. When the loaded crane is to be swung in its bearings 2 the clutch is first disengaged to uncouple the sleeve from the shaft, and when the crane has swung into operative position as in Figure 1 the clutch is also engaged.

The clutch sleeve is fashioned with a pair of angular arms 10 and 11, and to the free end of the arm 11 a retracting spring 12 is connected, said spring being anchored to a

bracket 13 fixed to the car roof, and designed to return the crane to inoperative position with the bag supporting arms pointing in the direction of travel of the car.

5 For cushioning and absorbing the shock of impact when the crane is performing its functions, an air cylinder 14 is pivotally suspended between the bracket 13 and the arm 10, the stem 15 of the piston not shown 10 within the cylinder being pivoted at 16 to the arm 10 as shown.

The crane when in operative position is positively held stationary through the co-action of an extension 17 of the arm 10, said 15 extension having journaled at its free end a roller 18 which is designed to engage and be held by a retaining device 19 attached to the roof of the car and specifically set forth in my co-pending application for Patent 20 Ser. No. 660,617, filed September 1, 1923.

For swinging the crane to projected operative position as shown in Figures 1 and 2 for the purpose of receiving a mail bag in the fork 5, I employ means operable from 25 the interior of the car and comprising a pull cable attached to an arm or fork 20 of the main angular arm 10. A cable or other flexible member 21, having at its free end a handle 22, is attached to the free end of 30 the fork 20, and a bracket 23, which is attached to the roof and clerestory frame of the car, is provided with a swiveled guide pulley 24 over which the cable passes. The pulley is swiveled in a lug 25 of the bracket, 35 and the cable passes from the pulley down through a perforation or slot 26 at the base of the bracket and thence through the car roof as seen in Figure 1. An eyelet or guide thimble 27 is also provided in the ceiling of 40 the car for guiding the movement of the cable. These guide devices 26 and 27 as well as the swiveled pulley 24 are designed to reduce to a minimum the friction and consequent wear on the cable as it is manipulated. 45 The bracket casting around the opening 26 for the cable is provided with a raised portion 26', as seen in Figure 3, which faces to the front of the car or in the direction of travel of the car, in order that dust, cinders, 50 or rain striking at this point will be passed upward and outward away from the opening 26, causing a slight vacuum behind the upraised lip 26' and creating a current of air to carry the cinders away from the opening 26. By a pull on the handle 22 it will be apparent that the crane with its fork may be swung against the tension of the spring 12 into the position of Figures 1 and 2 in 55 order that the fork 5 may receive a bag or mail pouch. In this position the crane is retained by co-action of the roller 18 and retaining device 19. As the crane is swung to the rear by impact of the received bag, its rotary motion is absorbed by the action of 60 the pneumatic device, and the spring 12 65

holds the crane in position for unloading. After unloading, the clutch may be released, and the crane pushed outwardly in order that the retracting spring by contraction may pull the crane around to inoperative 70 position.

Means are also provided for pulling the projected crane back across the doorway, as in loading position, and for this purpose a retracting cable or flexible member 28, having a handle 29 within the car, is passed through a thimble 30 in the ceiling of the car and a complementary thimble 31 in the roof of the car, and the outer end of the cable is attached to the arm 11 by means of 80 a link as 32. While the cable 21 in Figure 2 at the right is pulled to its limit within the car, it will be apparent that the cable 28 may be pulled within the car to draw or swing the crane from its projected position 85 back across the doorway for any purpose desired or required.

Having thus fully described my invention, what I claim as new and desire to secure by Letters Patent is—

1. A railway exchange device including a rotary crane, means for absorbing the shock of impact and means for moving said crane to inoperative position, manually operable means for swinging said crane to operative 95 position, and means including members detachable under impact on the crane for retaining said crane in stationary operative position.

2. A rotary crane supported exterior of 100 a car, a spring device for holding said crane in inoperative position, means operable from the interior of the car for swinging said crane to operative position, means including members detachable under impact on the crane for temporarily retaining the crane in operative position, and means for absorbing the shock of impact from a received mail bag.

3. A rotary crane exterior of a car, 110 resilient means for retaining said crane in inoperative position, a lever arm on the crane and a flexible cable operable from the interior of the car for swinging the crane to receiving position, means for temporarily retaining the crane in receiving position, and means for absorbing the shock of impact.

4. A rotary crane exterior of the car, a retracting spring, a lever arm on the crane and a flexible pull member operable from the interior of the car for swinging the crane to receiving position, means for temporarily retaining the crane in receiving position, and a pneumatic shock absorbing device.

5. A rotary crane exterior of a car, a retracting spring, a forked lever arm on the crane, flexible pull members operable from the interior of the car and connected with said forked lever arm for selectively swinging said crane to receiving position or load.

ing position, means for temporarily retaining the crane in receiving position, and means for absorbing the shock of impact.

6. The combination with a rotary crane having a lever arm and supported exterior of a car, of a pull cable attached to said arm and operable from the interior of the car, a supporting bracket having a swiveled pulley for said cable, and said bracket having a cable-opening with a raised wall to perform the function of a cinder-shield.

7. The combination in a railway mail ex-

changing device including a rotary crane having lever arms rotatable therewith, of means for swinging the crane to operative position, 15 a pneumatic shock absorbing device connected to one lever arm, means releasable under impact for retaining the crane in operative position, and a retracting spring operatively connected to the other lever arm, said spring 20 tending to resist accidental displacement of the crane from operative position.

In testimony whereof I affix my signature.

HERBERT E. SMITH.
